UNITED STATES PATENT OFFICE.

THOMAS HOWARD HOLROYD, OF SOUTHFIELDS, ENGLAND.

NON-REFILLABLE BOTTLE.

1,107,790.

Specification of Letters Patent. Patented Aug. 18, 1914.

Application filed December 21, 1912. Serial No. 738,028.

To all whom it may concern:

Be it known that I, THOMAS HOWARD HOLROYD, a subject of His Majesty the King of England, residing at 41 West Hill road, 5 Southfields, in the county of Surrey, Kingdom of England, have invented a certain new and useful Improved Non-Refillable Bottle, of which the following is a specification.

10 This invention relates to an improved non-refillable bottle and a non-detachable valve therefor, and has for its object to provide a device of simple construction which will effectively prevent the introduction of liquids or solids into bottles or vessels when once they have been filled and thus render the substitution of goods under other manufacturers' labels impossible.

15 The drawings show a convenient manner of carrying out this invention with regard to a bottle in which drawings:

Figure 1 is a sectional elevational view, and Fig. 2 a section on the line 2—2 of Fig. 1.

20 A tubular or hollowed member composed of preferably three parts *a*, *b*, *c*, secured together, is inserted into the neck *d* of the bottle, and the top portion *a* of the member is provided with one or more internally arranged baffle plates *a'* and with a cap *e* adapted to fit over and around the edge of the top or mouth *f* of the bottle neck.

25 The central portion *b* of the member is provided with one or more internal baffle plates as shown at *g*, and is formed with a chamber *h* adapted to inclose the cup-shaped head *i* of a valve the stem *j* of which slidably fits in the bottom portion *c* of the member. The valve is adapted to seat upon the top 30 edge *k* of the bottom portion.

35 The dogs *l* are pivotally mounted in the lower end of the member *c* and are adapted to be normally thrown outward by the resiliency of the rubber ring *m* surrounding

40 the member *c* just above the dogs and bearing thereagainst. Upon inserting the member *c* into the neck of the bottle as shown, the dogs *l* lie against the sides of the member *c*, however, when the member *c* reaches 45 its final position the dogs are thrown outward against the sides of the bottle neck by reason of the resiliency of the ring *m*, and since they are not adapted to fold down-

wardly any attempt to withdraw the member *c* from the neck of the bottle is met by 55 the resistance of the dogs *l*.

The baffle plates *g* are so shaped that they prevent the valve *i*, *j* being lifted from its seat *h* by the insertion of a wire or an implement, and if an attempt is made to pour 60 liquid into the bottle they will guide said liquid into the cup-shaped head *i* of the valve and force the same upon its seat.

The cap *e* is preferably undercut or grooved at *e'* and communicates by means of 65 a duct *e''* with the interior of the bottle or vessel, to provide air for pouring and should an attempt be made to lift the valve from its seat, and to withdraw the contents of the bottle by suction, air will pass through the 70 grooves and the chamber into the bottle to replace the outgoing liquid. The cap is preferably internally screw-threaded as shown at *n* to receive a screw-stopper or pouring funnel or the like (not shown). 75

When the bottle is empty and it is desired to remove the above-described device therefrom it is necessary to break the bottle neck to do so, thus it will be seen that the present invention provides a non-detachable, 80 device which will render a bottle absolutely non-refillable by fraudulent means, and prevents tampering with the same in any way.

The top portion *a* of the member is shaped to take flexible material such as cork, rubber 85 or leather *o*, to fit tight and closely to the neck of the bottle thus preventing leakage, also causing the bottle to remain air tight and giving a rigidity to the member. The lower portion *c* of the member is preferably 90 fitted with a cork, rubber, or other centrally perforated washer *p* which would prevent liquid in the bottle or vessel flowing to and corroding the expanding devices and other parts, and said washer may carry a mica or 95 other disk or label *q*, descriptive of the contents of the bottle.

In operation the device is inserted in the neck of the bottle after the bottle has been filled. When the dogs *l* move into the enlarged portion of the bottle neck the resiliency action of the rubber band *m* forces them outward as shown and prevents withdrawal of the device. Upon tilting the bottle the contents flow out through the central 105 passage, the valve moving away from its

2
seat and passing around the baffle plate out of the mouth. At the same time air can enter through the passage e^2 .

What I claim as my invention and desire 5 to secure by Letters Patent of the United States is:

The combination with a bottle provided with a neck having an interior shoulder; of a valve structure adapted to be inserted in 15 said neck with its lower end projecting below said shoulder, lugs projecting from the lower end of the valve structure and provided with slots extending outwardly from

said lower ends, dogs provided with pins engaged in said slots whereby said dogs have 15 a pivotal and sliding connection with the valve structure, and means carried by the valve structure to force said dogs outwardly.

In testimony whereof I have signed this specification in the presence of two sub- 20 scribing witnesses.

T. HOWARD HOLROYD.
